ELECTRIC IGNITION AND STARTING APPARATUS FOR INTERNAL COMBUSTION ENGINES

Application filed February 13, 1932. Serial No. 592,808.

The conventional internal combustion engine that is now used practically universally on power-operated vehicles and motor boats is provided with an electrical ignition and starting apparatus that comprises a single storage battery which is used to supply electric current to the ignition mechanism and also to the starting motor that turns the crank shaft of the engine in the operation of starting the engine. When the engine is being started the starting motor imposes a heavy load on said battery and this frequently results in the ignition mechanism not receiving sufficient current to produce a "spark" that will ignite the fuel in one or more cylinders of the engine. This inherent characteristic of the conventional electrical ignition and starting apparatus is particularly noticeable when the battery is weak, and also in cold weather when the compression is reduced, due to the lubricating oil of the engine being stiff and having drained away from the piston rings after being idle for some time. It is objectionable not only in that it frequently results in failure of the spark plugs to produce sparks of sufficient intensity to quickly ignite the combustible mixture in the cold cylinders, but also because it results in excessive waste of fuel in the operation of starting the engine, due to the pistons reciprocating a number of times, and thus drawing considerable fuel into the cylinders, before the ignition mechanism produces a spark that will ignite the fuel. If the starting motor is operated frequently, or if the starting motor is continued in operation for a long period in an endeavor to start a cold engine, there is great danger of running down the battery, thus making it necessary to remove the battery and replace it with a fully charged battery before the engine can be started. Moreover, if the battery is also used to supply electric current to a lighting system, as is the usual practice, excessive or abnormal use of the lighting system, as, for example, considerable night driving with little or no day driving, or use for long periods of a parking light, causes the battery to become so low or weak that

it is not capable of operating the starting motor.

Our invention has for its main object to overcome the above mentioned defects or objectionable characteristics of the conventional electrical ignition and starting apparatus now generally used on internal combustion engines. To this end we have devised an electrical ignition and starting apparatus that comprises or is equipped with two batteries or other sources of electrical energy or power, one for the starting motor and the other for the ignition mechanism, and means for causing the battery that is associated with the starting motor to be disconnected or uncoupled from the battery that is associated with the ignition mechanism in the operation of starting the engine, whereby diminution in the supply of electric current to the ignition mechanism during the starting operation is absolutely eliminated; due to the impossibility of the starting motor exerting a load on the ignition battery. Our invention insures quicker starting of an internal combustion engine, especially in extremely cold weather; it eliminates excessive waste of fuel in the starting operation; it greatly reduces the liability of running down or exhausting the battery used to operate the starting motor, and it greatly reduces the liability of failure of the supply of electric current used to energize the starting motor, caused by excessive or abnormal use of a lighting system that receives its supply of current from the source of power used to energize the starting mechanism. It also improves or increases the efficiency of the ignition mechanism of an internal combustion engine by increasing the sources of supply of electrical energy for the spark plugs when the engine is in operation.

If desired, the apparatus can be constructed in such a way that if one battery becomes exhausted or run down, the user, by manipulating devices, as shown, can bring the other battery into service, as, for example, to operate the starting motor in the event of failure of the starting motor battery, or to operate the ignition mechanism or ignition mechanism and lighting system, or use both

batteries to operate the starting motor, in the event of failure of the battery that is normally used to energize the same. Our invention is applicable to various types and kinds of internal combustion engines used for various purposes and does not contemplate and is not restricted to the use of any particular type or kind of starting apparatus, ignition mechanism or ignition mechanism and lighting system.

Figure 1 of the drawing is a diagrammatic view, illustrating our invention applied to a conventional power-operated vehicle, such as an automobile, equipped with an internal combustion engine, an ignition mechanism comprising spark plugs, a lighting system, and an electrical generator operated by the engine; and

Figure 2 is a vertical sectional view of one form of switch that may be used to disconnect or uncouple one battery, hereinafter referred to as the starting battery, from the other battery, hereinafter referred to as the ignition battery, during the operation of starting the engine.

In the accompanying drawing, which, as previously stated, is intended to diagrammatically illustrate our invention, A designates a conventional internal combustion engine mounted on the chassis B of an automobile. C designates spark plugs for igniting the combustible charges of fuel supplied to the cylinders of said engine, D designates the high tension coil and E designates the distributor of the ignition mechanism, F designates an electrical generator with its conventional cut-out F' operated by the engine, G designates an ammeter, H designates electrically-operated lamps, such as headlights, that form part of a lighting system, I designates a switch for controlling the lighting circuit, J designates a switch for controlling the spark plug circuit, W designates a switch that co-acts with the switch J for disconnecting the lighting system from the starting battery when the ignition switch J is opened, and K designates a starting motor, the parts above referred to being connected together and grounded to the frame B of the chassis in a conventional manner.

Instead of using a single battery to operate the starting motor K and also to supply electrical energy to the ignition mechanism and lighting system, as has heretofore been the usual practice, we employ one battery L to supply electric current to the starting motor K and a separate and distinct battery M to supply electric current to the ignition mechanism, or to the ignition mechanism and lighting system, during the operation of starting. We also use a manually-operated switch, designated as an entirety by the reference character N, to disconnect or uncouple the ignition battery M and the generator F from the starting battery L during the oper-

ation of starting the engine A, so as to effectively prevent the starting motor K from exerting a load on the ignition battery M. It should be understood that if this disconnection is accomplished by the use of an electromagnetic circuit breaker or other electrical "cut-out", it is still within the spirit of the invention.

The switch N just referred to can be constructed in various ways without departing from the spirit of our invention, so long as it is of such design that when it is actuated to establish electrical connection between the battery L and the starting motor K, it will be impossible for electric current to pass from the ignition battery M to the starting motor K. We prefer to construct the apparatus in such a manner that when the engine is in operation the generator will supply electric current to both of the batteries L and M and the ignition and lighting systems. The switch N herein illustrated comprises a contact 1 connected by a lead 2 to the starting motor K, a contact 3 connected by a lead 4 with the starting battery L, and a conducting element 5 attached preferably to a spring-actuated foot plunger 6 and adapted to be moved into engagement with the contacts 1 and 3, so as to establish electrical connection between the leads 2 and 4, and thus permit current to pass from the battery L to the starting motor K. Said switch N is also provided with two additional contacts 7 and 8 that are normally in engagement with the conducting element 5, but which are adapted to be disconnected from the same during the operation of starting the engine. The contact 7 is connected by a lead 9 with the ammeter G, and by a lead 10 with the ignition battery M, and the contact 8 is connected through the switch W by a lead 11 with the contact 3 so as to establish electrical connection between the generator F and both of the batteries L and M when the switch N is in its normal open position, and to automatically disconnect or uncouple the starting battery L from the ignition battery M and the generator when said switch N is moved into its closed position during the operation of starting the engine.

Figure 1 of the drawing illustrates the switch N in the position it occupies when the engine A is in operation. At such times the conducting element 5 of said switch establishes electrical connection between the contacts 7 and 8, with the result that the electric current produced by the generator F will be supplied to both of the batteries L and M, and electric current will be supplied from the ignition battery M from both batteries M and L and generator to the ignition mechanism and to the lighting system, assuming, of course, that the switches J, I and W are closed. In the operation of starting the engine A the plunger 6 of the switch N is moved

into the position shown in Figure 2 so as to disconnect the conducting element 5 from the contacts 7 and 8 and move said conducting element 5 into engagement with the contacts 5 1 and 3. In this position of the switch N the starting battery is disconnected from the ignition battery and also from the generator. As soon as the user releases the plunger 6 of the switch N, the expansion spring 6^a that is 10 associated with said plunger moves the same in a direction to disengage the conducting element 5 from the contacts 1 and 3 and restore said conducting element to its normal position in engagement with the contacts 7 15 and 8.

With an ignition and starting apparatus of the construction above described an ample supply of electric current for the spark plug C is assured during the operation of starting 20 the engine, due to the fact that separate and distinct sources of supply of electric current are provided for the starting motor K and for the ignition mechanism, and in the operation of starting the engine, there is no 25 chance for the starting motor K to drain or exert a load on the ignition battery M. If the ignition battery M is in a properly charged condition, the engine will start more quickly, especially when it is cold, thereby 30 effecting a considerable saving in fuel and reducing the liability of running down the battery used to operate the starting motor. Both of the batteries L and M are kept in a properly charged condition, because both of 35 said batteries are normally connected with the generator G, and excessive or unusual use of the lighting system is not liable to result in the starting motor failing to operate when it is desired to start the motor, because 40 the turning off of the ignition switch J which is made to co-act with the switch W, disconnects the lighting circuit from the starting battery, thus preserving the charge in the starting battery when the ignition battery 45 is used for lighting purposes while the engine is idle. The increase in the supply of electric current for the spark plugs afforded by the extra battery also improves or increases the 50 efficiency of the ignition mechanism of the engine.

If desired, a lead 12 provided with a control switch 12^a, can be arranged between the ignition battery M and the contact 3 of the switch N, so as to enable the user to bring 55 the battery M into service to supply electric current to the starting motor K in the event the starting battery L runs down or becomes so weak that it will not operate the starting motor alone. This is highly desirable, in that 60 it gives the user the assurance of always having on hand an extra battery for the starting motor, in the event of failure of the battery that is normally used to energize the starting motor. Likewise, in the event of failure 65 of the ignition battery M, the user, by closing

the switch 12^a, can couple up the starting battery L with the ignition mechanism and lighting system. Also, if desired, a switch 12^b can be arranged, as shown in the lead 4, 70 to isolate the starting battery, in case of its complete failure. Normally, the switch 12^a is in an open condition, and switch 12^b is in a closed position, as shown in Figure 1.

In addition to the advantages previously pointed out, our invention overcomes an inherent defect of automobiles and other power-operated vehicles of the "free wheeling" type equipped with a single battery. In the conventional automobile equipped with a "free wheeling" mechanism that permits the 75 automobile to coast and the engine to rotate at a relatively slow speed under certain conditions, there is a tendency for the storage battery to run down quickly because when the automobile is coasting, the engine is operating at such a speed that the generator will not charge the battery. This is necessary in an automobile equipped with a single battery, because if the generator were set so as 80 to charge the battery when the automobile is coasting, the rate of discharge of the electric current from the generator would be so high, under normal conditions, i. e., when the engine is coupled up with the propelling 85 mechanism of the automobile, that the battery would become overcharged or ruined by the supply of too great a quantity of electric current to the battery. With our invention, which contemplates the use of two batteries, 90 this cannot occur, because the generator can be stepped up to double the charging rate, say, 25 amperes, whereby electric current will be supplied to the batteries at low engine speeds when the automobile is coasting. Subsequently, when the engine operates at a 95 higher speed or at normal speed, the rate of electrical discharge from the generator will be proportionately increased, but without danger of harming the batteries, due, of course, to the fact that the battery capacity 100 is sufficient to take care of the electric current that is produced when the automobile is operating under normal conditions.

Having thus described our invention, what 115 we claim and desire to secure by Letters Patent is:

1. In an internal combustion engine, the combination of an electric ignition mechanism, an electrically-operated starting means, 120 an electric lighting system, a storage battery for supplying current to said starting means, a separate and distinct storage battery for supplying current to said ignition mechanism and lighting system, means for supplying electrical energy to the two batteries, and means whereby the user may employ the starting battery to supply current to the ignition mechanism or may employ the ignition 125 battery to supply current to the starting 130

means, or use both storage batteries together to supply current to the starting means.

2. An electric circuit for internal combustion engines including spark plugs for igniting the fuel supplied to the cylinders of the engine, a lighting system, a starting motor, an electric generator, a starting battery, an ignition battery, a control switch, said control switch having provision for normally connecting both of said batteries with the spark plugs and with the lighting system and generator when the engine is in normal operation and for uncoupling the starting battery from the elements with which it is normally connected and for establishing electrical connection between said starting battery and the starting motor during the operation of starting the engine, and a means by which the user can employ the ignition battery to operate the starting motor when the starting battery fails.
